WORK SUPPORTING ROLL FOR POLISHING MACHINES

Alfred J. Sandorff, Niagara Falls, N. Y., assignor to General Abrasive Company, Inc., a corporation of New York

Application December 18, 1935, Serial No. 55,118

3 Claims. (Cl. 51—78)

This invention relates to polishing machines for polishing thin metal sheets, and more particularly to a method of polishing such sheets and to improved constructions of the polishing wheel and the feed roll for use in such machines.

A polishing tool of the type heretofore used for such purposes is not flexible during the polishing operation. On account of this action of the wheel its operating face is not permitted to become accommodated to any of the surface imperfections or irregularities of the work sheet during polishing, hence, it has been found necessary with the prior polishing, wheels to make many passes of the work back and forth under the wheel during the polishing operation until the superficial high portions of the work have become polished down to substantially the general level of the depressed areas thereof before the surface of the final sheet could be provided with a satisfactory and uniform polish.

It is accordingly an object of the invention to overcome such prior difficulties and to provide a simple, efficient and improved method of polishing thin metal sheets having various conditions of surface texture.

Another object of the invention is the provision of means whereby metal sheets may be polished on one of the surfaces irrespective of any irregular surface effects therein.

A further object of the invention is to provide an improved supporting body for the work sheet to be polished which will enable the polishing wheel to reproduce on the work a polished surface irrespective of the contour and texture of the original surface of the work.

With these and other objects in view, the invention consists in the steps of the method and of certain novel features of construction, as will be more fully described, and particularly pointed out in the appended claims.

In the accompanying drawing:

Fig. 1 is a partial diagrammatic view, in elevation, illustrating a polishing machine embodying my invention in operative relationship with respect to a sheet of work;

Fig. 2 is a diagrammatic top plan view of the polishing apparatus shown in Figure 1;

Fig. 3 is a fragmentary cross-sectional view of a portion of a feed roll formed in accordance with my invention;

Fig. 4 is a fragmentary longitudinal sectional view of the roll structure shown in Figure 3;

Fig. 5 is a fragmentary longitudinal view, in section, of an abrasive polishing wheel embodying a feature of the invention;

Fig. 6 is a fragmentary cross-sectional view of a portion of a work supporting and feed roll illustrating a modified construction thereof incorporating my invention; and

Fig. 7 is a fragmentary cross-sectional view showing another modification of the invention as applied to the feed roll construction.

In accordance with my invention, I have discovered that thin metal sheets having various conditions of surface texture, irregularities, such as depressions and the like, may be provided with a satisfactory polished surface if the lower support for the sheet is made of such a character that it will permit deformation of the irregular surface portions carried by the surface of the sheet which is being acted upon by the polishing wheel during its passage thereunder. I therefore propose to provide a yieldable supporting member for the metal sheet and preferably a roll having a resilient or yieldable outer surface portion which will contact with the under surface of the sheet of work, and to accomplish the polishing operation on the upper face of the sheet by means of a hard, substantially inflexible abrasive polishing body or roll which is so arranged with respect to the lower supporting roll as to contact with the upper surface of the sheet to polish the same as the sheet is continuously and progressively fed thereunder. Thus, the sheet is so supported during its passage beneath the polishing roll that the pressure incident to the polishing operation causes temporary deformation of those irregularities on its upper surface to force them into contact with the polishing wheel while any thick places in the work are depressed into the resilient outer covering of the lower supporting roll as the sheet passes between the rolls.

With reference to the drawing, one specific embodiment of the invention shown in Figures 1 to 5, inclusive, comprises a polishing wheel 10 rotatably mounted on a shaft 12, the wheel being arranged in contact with one side of a sheet of work 13 which in turn is supported on its under side by supporting roll or drum 14 of a yieldable construction and mounted for rotation on a shaft 15, the sheet being continuously and progressively advanced between the rolls and fed therethrough at the speed desired. The rolls 10 and 14, respectively, are mounted to rotate in opposite directions, the polishing roll 10 being suitably driven at high speed from any appropriate source of power while the lower work supporting roll 14 is adapted to travel at a slow speed whereby its yieldable characteristic may be maintained. A suitable conduit 16 is provided to

be used in conjunction with the polishing wheel 10 so as to discharge a fluid coolant, such as water, from the nozzles 17 into the polishing zone of the polishing wheel and the work. The work sheet 13 may be fed either by the feed rolls 18, as shown in Figure 1, which are mounted on one side of the work surface and the rolls 19 on the other side thereof or the supporting roll 14 may be utilized to act upon the under side of the sheet 13 to impart movement of the sheet between the rolls 10 and 14, respectively.

The polishing wheel 10 may be of any suitable rigid and substantially non-yieldable construction, but as illustrated in the drawing, Figure 5, it preferably consists of a hard external outer layer or portion 20 forming an abrasive sleeve on the drum and composed of a mixture of abrasive grains and hard vulcanized rubber integrally uniting the grains together, the layer 20 being secured by vulcanization to an inner fabric sleeve 21. The sleeves 20 and 21 may be mounted directly on a solid central drum 22 or they may be affixed to a suitable hollow metal cylinder which in turn may be removably mounted upon 25 and secured to the metal drum 22. If desired, the polishing wheel surface may be provided with a coolant conductive groove, or the wheel may be formed with a relatively smooth and substantially continuous polishing surface. If the former construction, the sleeve may be bound on the drum 22 by means of a suitable binding wire 23 wound in the coolant conducting groove. The ends of the wire may be secured in any suitable manner, as by a clamping screw 24. This abrasive portion 20 of the polishing wheel may be made by various methods, the grooved sleeve being formed with an inner fabric sleeve which is first prepared by winding a strip of fabric around a metal cylinder after which the rubber 40 and abrasive element is applied thereto either as a wound strip of the extruded rubber and abrasive mixture, or I may employ a flexible or plastic mixture of the rubber and abrasive grains which is molded "in situ" around the fabric sleeve, this latter method being more fully described and claimed in my co-pending application, Serial No. 55,115, filed December 18, 1935. The abrasive grains employed may be of any suitable grit size and are selected in accordance with the polishing 50 properties desired in the finished wheel and the physical characteristics of the sheet material to be polished.

In order that the surface irregularities of the metal sheet may be deformed momentarily into the surface of the lower roll 14 during the polishing operation, I have constructed the roll 14 which supports the sheet with a deformable outer covering layer 25 composed of a resilient or yieldable material, such as soft vulcanized rubber, leather or cork, the layer 25 being affixed to an inner fabric sleeve 26 and the whole structure being either directly mounted upon or removably secured to a central drum or support 28. If soft rubber is preferred for the layer 25 I may make this portion by either wrapping a strip of fabric around the metal center and winding sheets of soft rubber about the fabric layer to build it up to the desired thickness, or by molding a plastic rubber composition "in situ" about the fabric sleeve; and in both cases, the rubber is subsequently vulcanized to form soft, vulcanized rubber.

If desired, a modified construction as shown in Figure 6 may be used in which the fabric sleeve 26, shown in Figure 3, between the outer resilient

layer 25 and the central drum 28 is eliminated, and the soft rubber outer layer 30 vulcanized directly to the central drum 28. In this case, the surface of the drum may be preliminarily treated in accordance with any practice in the art, such as brass plating, prior to forming the rubber layer 30 thereon in order to provide good adhesion of the rubber to metal surfaces after vulcanizing the rubber. 5

In Figure 7, I have illustrated another modified construction of work supporting roll 14 which is feasible and incorporating a yieldable outer work engaging portion. In this construction, the soft rubber outer covering layer 33 is vulcanized directly to a metal sleeve 34 after which the entire sleeve structure may be mounted in any suitable manner on the drum 28 for rotation therewith. The sleeve 34 may likewise be suitably treated, as by brass plating its outer surface, in order that the rubber layer 33 will firmly stick thereto after 20 vulcanization of the rubber.

It will now be apparent that my invention provides an improved mode of polishing thin metal sheets, since the present arrangement is not one which is dependent upon any yieldability of the structure of the polishing element as heretofore proposed, but it now transfers the yieldable feature to the lower supporting roll for the sheet whereby the surface irregularities present upon the upper face of the sheet are pressed into the 30 yieldable surface layer of the lower roll as they pass under the polishing wheel and the surface contacted thereby is polished without permanent change in the original irregular surface of the sheet. 35

The foregoing description is directed solely towards the construction illustrated, but I desire it to be understood that I reserve the privilege of resorting to all the mechanical changes to which the device is susceptible the invention being defined and limited only by the terms of the appended claims. 40

I claim:

1. In a machine for polishing thin metal sheets, a work support roll therefor comprising a central cylindrical support provided with an outer work engaging portion in the form of a sleeve consisting of a layer of cork. 45

2. In a machine for polishing thin metal sheets, a rigid polishing wheel, feed rolls arranged at opposite sides of the axis of said polishing wheel, and a work support roll positioned between the feed rolls and beneath said polishing wheel, said support roll having an outer work engaging portion comprising a thick layer of cork which is 50 adapted to yield when in contact against the bottom face of the sheet being polished and during its travel between said support roll and the polishing wheel to cause an unbroken line of contact between the work surface of the sheet and 60 the polishing wheel.

3. In a machine for polishing thin metal sheets, a work support roll therefor comprising a central cylindrical support, a layer of fabric secured thereto, and an outer work-engaging portion 65 comprising a thick layer of cork superimposed over said fabric layer and integrally united thereto, said outer layer of cork being adapted to yield when in contact against the lower face of the sheet being polished and during its travel between said support roll and the polishing tool to cause an unbroken line of contact between the work surface and the polishing tool. 70
